UNITED STATES PATENT OFFICE.

FRANK ANSTETT, OF WILKESBARRE, PENNSYLVANIA.

ELECTRIC RAILWAY.

SPECIFICATION forming part of Letters Patent No. 780,698, dated January 24, 1905.

Application filed August 9, 1904. Serial No. 220,091.

To all whom it may concern:

Be it known that I, FRANK ANSTETT, a resident of Wilkesbarre, in the county of Luzerne and State of Pennsylvania, have invented certain new and useful Improvements in Electric Railways; and I do hereby declare the following to be a full, clear, and exact description of the invention, such as will enable others skilled in the art to which it appertains to make and

5 use the same.

My invention relates to an improvement in electric railways, and more particularly to third-rail systems, the object of the invention being to provide an improved construction of 15 third rail and shoe to make contact therewith; and the invention consists in certain novel features of construction and combinations and arrangements of parts, as will be more fully hereinafter described, and pointed out in the

20 claims.

In the accompanying drawings, Figure 1 is a view in cross-section, illustrating my improvements. Fig. 2 is a plan view. Fig. 3 is an enlarged view of the shoe, and Fig. 4 is 25 an enlarged view of the third rail in cross-section.

1 represents the rails of a track secured on ties 2, which latter also support my improved third rail 3.

30 4 represents a car-truck of any approved construction, to which a depending arm 5 is secured and carries my improved shoe 6. At the lower end of arm 5 a horizontal outwardly-projecting rectangular box 7 is secured and 35 has a cross-pin 8 therein, which passes through an elongated slot 8^a in the shoe 6, and a coiled spring 10 is located between the end of the shoe and the inner end of the box to compensate for lateral movement of the truck and

40 always maintain the shoe in contact with the third rail 3.

Shoe 6 comprises two sections, one of which is bifurcated to receive a lug 11 on the other, and a pin 12 is passed through both sections 45 to pivotally connect them together. The outer section carries a beveled contact-block 13, which is always maintained in contact with the under face of the third rail by a flat spring 14, which latter is secured to the bottom of box 7 at one end and at its other end exerts

upward pressure on the outer hinged section of the shoe to maintain the contact-block against the third rail.

The third rail 3 is of inverted-L shape in cross-section and is beveled at its ends to permit the contact-block 13 to readily move into operative position beneath the same. On the rail 3 at regular intervals rubber or other non-conducting or insulating strips 15 are located, and a framework of wood, as shown at 55 16, is secured over the rubber strips 15, and a metal casing 17 is secured over the wooden framework. By so constructing the rail it is protected from snow and ice, which would interfere with the perfect contact of shoe, and 60 the rail is perfectly insulated and protected by the covering above described.

A great many slight changes might be made in the general form and arrangement of the parts described without departing from my 70 invention, and hence I would have it understood that I do not restrict myself to the precise details set forth, but consider myself at liberty to make such slight changes and alterations as fairly fall within the spirit and scope 75 of my invention.

Having fully described my invention, what I claim as new, and desire to secure by Letters Patent, is—

1. In an apparatus of the character described, the combination of a truck, of a box secured thereto, a shoe comprising two members pivoted together, one of said members mounted in said box having an elongated slot 80 therein, a cross-pin in the box projecting 85 through said slot, and a spring behind the members of the shoe in the box exerting outward pressure thereon to compensate for movement of the truck.

2. In an apparatus of the character described, the combination with a truck, of an outwardly-spring-pressed shoe carried thereby, said shoe comprising two members pivoted together and a spring pressing the outer member of said shoe upward. 90

3. In an apparatus of the character described, the combination with a truck, of a shoe connected therewith and comprising two sections hinged together end to end, a spring 95 normally pressing the outer section of said 100

shoe upward, and a spring pressing both of said sections outwardly.

4. In an apparatus of the character described, the combination with a truck, a depending arm thereon, and a horizontal box secured to said arm, a shoe comprising two members, pivoted together end to end, one member having sliding connection with the box, a spring pressing said members of the shoe outward to compensate for movement of the truck, a spring secured to the bottom of

said box and pressing against the under outer member of the shoe to hold its contact-block against a third rail.

In testimony whereof I have signed this 15 specification in the presence of two subscribing witnesses.

FRANK ANSTETT.
